UNITED STATES PATENT OFFICE.

MANUEL S. AYAU, OF NEW YORK, N. Y.

PRINTING-TELEGRAPH.

1,006,344.

Specification of Letters Patent. Patented Oct. 17, 1911.

Application filed November 14, 1907. Serial No. 402,224.

To all whom it may concern:

Be it known that I, MANUEL S. AYAU, a resident of the city of New York, in the county of New York and State of New York, have invented new and useful Improvements in Printing-Telegraph, of which the following is a specification.

This invention relates to an improved system of connecting and operating type-writing mechanism on an electrical circuit between a station at one end of a main-line or circuit, and one or more stations on the circuit; also to electro-mechanical apparatus of novel construction operating to type-write or permanently record at the sending-station simultaneously with the transmission, the words or matter being transmitted, and to reproduce the same matter in type-written form at the receiving-station.

The invention has for its objects to operate type-writing mechanism on an electrical circuit between transmitting and receiving stations over a single main-line or circuit; to reduce the number of conductors between the stations or apparatus to a single metallic circuit, or to a single line-wire and an earth-return, without the employment of synchronized instruments or polarized relays; and to enable words and other matter to be transmitted, and also to be recorded by the instruments or apparatus at a station, whether the same be operating at the time as a transmitting apparatus, or as a receiving apparatus.

To these ends and objects, chiefly, the improved system of my invention comprises a keyboard-operated transmitting-mechanism at one end of an electrical circuit, including means for sending over the line by the single stroke or depression of a key a predetermined number of electrical impulses individual to that key, but of a relatively low potentiality, followed by a single impulse of a higher potentiality; and combined therewith a recording-apparatus at the receiving-end of the circuit, consisting principally of electrically-actuated type-writing mechanism in which the actuating-means of each type-bar is normally in open circuit with a local battery through circuit-closing devices individual to that type-bar and to none other, and so arranged as to be selected and put in operation to set up a circuit through the battery and the type-bar op-

erating mechanism by a fixed and definite number of electrical impulses that are transmitted by the operation of the particular key corresponding to the letter or character to be written. By the definite number of electrical impulses transmitted by a particular key on the key-board at the sending-station the weaker impulses sent over the line act through the selecting-devices to set up for operation the local circuit which is individual to the actuating-mechanism of the particular type-bar to be operated; and by the stronger impulse following the successive selecting-impulses the type-bar at the receiving-station is actuated electrically, with the result to imprint or write the letter or character upon the paper in the writing-mechanism, in the usual manner. In addition to its function of operating the type-writing mechanism with which it is connected, each key actuates circuit-closing devices individual to itself and of such character or arrangement that every key in the keyboard will act to send over the line a predetermined number of electrical impulses peculiar to that key, followed by an impulse of higher potentiality, by a single stroke or depression of the key.

The mechanism at the sending-station for sending a definite number of electrical impulses over the line by the single depression or stroke of a letter or character-key, and the mechanism at the receiving-station through which such impulses are caused to select the corresponding type-bar actuating means and to operate the type-bar, constitute the principal features of the apparatus.

The means whereby the paper-carriage or platen of the type-writing mechanism is controlled and moved from the sending-station to properly space the words and the lines of the written matter at the receiving-station are reserved for a separate application for Letters Patent. It will be evident, however, to those skilled in the art to which this invention relates, and particularly to those familiar with the construction of electrically-operated type-writing machines, that the paper on which the matter is written by the type-bars at the receiving-station may be controlled over the same circuit by employing any of the well-known spacing-devices or mechanism of electrical type-writing machines, wherein the paper-car-

riage or holder is actuated to space the words and lines by means of a given number of electrical impulses produced at the sending-station and transmitted over the line by 5 operating a key in the sending key-board.

The aforesaid objects are attained and my said invention is produced and carried out by means of the mechanism, apparatus and electrical circuits described and set 10 forth in the following specification, in which the accompanying drawings illustrating the electrical circuits and the transmitting-apparatus and the receiving-apparatus of my invention are referred to by figures and letters. 15

Figure 1 is a plan or top-view of the key-board type-writing mechanism and circuit-closing devices at the sending station; the same also corresponding to, and being a 20 duplicate of the mechanism at the receiving-station, and constituting a receiving, as well as a sending apparatus. Parts of the stationary-frame and the movable mechanism and devices in this figure are broken away 25 to show more clearly the construction of inside parts. Fig. 2 is a longitudinal sectional view through Fig. 1, showing both the means employed to actuate the type-bars electrically from another station on the line, 30 and also the circuit-closing devices that are brought in play and operated by a particular key in the keyboard to transmit a given number of successive electrical impulses of the same potentiality, followed by a single 35 impulse of a higher potentiality, by a single stroke of the key. Fig. 3 is a plan or top-view of a portion of the transmitting apparatus provided at every station, and connected with the key-board; the same being 40 a top-view of the last four circuit-closing electro-magnets and their armatures and circuit-closing contacts in the series. Fig 4 is a vertical section taken transversely through Fig. 3 on a line $x-x$. Fig. 5 is a front-elevation, taken from the left side of Fig. 3, 45 but showing an additional one of the series of electro-magnets, armatures and circuit-closing contacts. Fig. 6 is a rear-elevation of the same, taken from the right side of Fig. 3. Fig. 7 is a plan or top-view of the 50 circuit-selecting apparatus situated at the receiving-end of the line at every station, and through which the electrical impulses sent over the line from the sending-station are caused to operate the type-bar mechanism of a particular letter or character, according to the number of impulses transmitted at any one time by the single stroke of the key at the sending-station. Fig. 8 55 is a front-elevation of Fig. 7, showing one tier or row of electro-magnets and their armatures and the circuit-closing contacts associated therewith. Fig. 9 is a vertical-section, taken transversely through Fig. 7 on 60 the line $y-y$. Figs. 10 and 11 are diagrams 65

representing the general arrangement of the transmitting and the receiving apparatus at two separate stations in circuit through a line-wire and an earth-return; and showing diagrammatically the local circuits and 70 sources of current and the type-bar actuating-means of a single letter or character key and type-bar. Fig. 12 is a diagrammatic representation of the local circuits and 75 circuit-closing devices of the last three electro-magnets in the transmitting apparatus provided at every station. Fig. 13 is a diagram in perspective of the local circuits and circuit-closing devices associated with six of the series of electro-magnets and their armatures in the circuit-selecting means at the 80 receiving-end of the line.

According to this invention the key-lever a of each type-bar b in a type-writing machine of well-known construction, such as 85 an "Oliver type-writer", on being pressed by the finger, operates in a single stroke to throw in circuit with a local battery, as E , the coils of a group or set of electro-magnets in successive order and in such manner that 90 a succession of electrical impulses of uniform duration and quality and of an invariable and definite number for each particular key are caused to pass out over the main-line W to a corresponding type-writing mechanism at the receiving-end of the line, through circuit closing devices operated by the magnets. Such impulses, herein termed the selecting-impulses, acting 95 upon a circuit-selecting means at the receiving-station have the effect to bring in circuit with, or connect into, the main-line W a key-operating means, such as a solenoid s and its core t , with which each key in the key-board is provided; and by the same 100 stroke of the key, but following the successive weaker impulses, a single impulse of a higher potentiality from a battery F is caused to pass out over the line, and through the solenoid-circuit already set up by the 105 selecting-mechanism before mentioned. The final circuit thus completed brings in operation a local battery G , the current from which operates the type-bar at that end of 110 the line on the completion of the stroke of the sending key at the opposite end. Thus by the usual movement of any key in the key-board in writing a letter or character, the two operations of selecting the operating 115 circuit of the type-bar in the mechanism at the receiving-station corresponding to the key that is struck at the sending-station, and of actuating the selected type-bar, are carried on and effected over a single line-wire or conductor by currents of one direction 120 and without synchronized instruments. These operations of selecting and setting up the actuating-circuit of a particular type-bar operating mechanism through the medium of initial series of impulses of a 125 130

tively low potentiality and a following single impulse of a higher potentiality in the case of every key in the transmitting mechanism, are effected by the transmitting-apparatus of my invention illustrated in Figs. 3, 4, 5 and 6, and the similar receiving-apparatus illustrated in Figs. 7, 8 and 9, with which every station on the main-circuit is provided, for operating the same at will to transmit, or to receive and record, words and matter in type-written form. The construction and operation of these two sets of apparatus will be described hereinafter with reference to their operating circuits illustrated in the diagrams Figs. 12 and 13.

In the following description it should be understood that both the mechanically-operated means and the electrically-operated means, and the circuits by and through which a key in the transmitting keyboard is caused to operate the proper type-bar in the writing-mechanism at the receiving-end of the line, are the same in the case of every letter or character represented in the keyboard by a key, and in the type-writing mechanism by a type-bar; so that the description of the construction and operation of the means and circuits through the medium of which one letter or character is transmitted, and is written or reproduced at the distant station is the same as, and will apply to, every other letter or character. The description of one key-operated means and devices herein given will therefore apply to all the remaining keys and writing-mechanism and their actuating means.

With each key-lever in the key-board of a typewriter of any well known construction are arranged two circuit closing contacts 2-3 of a local circuit in which are included the coils of a given number of electro-magnets each of which when energized operates to attract the front end of an armature-lever lying over the pole of the magnet. On drawing down that end of the armature the magnet when energized by current from a local battery E , operates to elevate the rear end of the lever and thereby complete a circuit through another battery E^x from the transmitting apparatus to the line wires leading out from the station.

Each key-lever is connected in the manner described with or into a certain magnet in the row or series M , M^1 etc. at a greater or less distance from the last magnet M , according to the particular letter or character in the key-board that the lever is adapted to print when depressed, and each key lever thus embraces in the particular circuit it controls, or is appropriated to, a fixed and definite number of magnets in the series M , M^1 , M^2 , and so on. According to the principle on which these circuit controlling magnets are arranged and connected, the last magnet M in the series will close the circuit

on the outgoing line and throw upon it a current of sufficient intensity to actuate circuit closing means in the apparatus in the receiving station at the other end of the line and thereby actuate the printing or writing mechanism in the apparatus provided at that end, following the electrical impulses which every other magnet in the series as selected and actuated may send out over the line.

The number of magnets that are associated and arranged with each particular key-lever to be set in operation by it are determined by the number of impulses that are required to actuate the circuit selecting means for the mechanism of the corresponding key at the receiving station. In every case, however, the particular number of magnets appropriated to the key-lever of any letter or character always includes the magnet M , which must be the last one in the series to be energized, because it controls the battery E^x from which an impulse of sufficient potential is sent out over the line to actuate the corresponding type-bar in the printing mechanism at the other end.

With each magnet in the series M , M^1 and so on, is arranged an armature lever T , T^1 , T^2 and so on, pivotally supported at 191 and having a contact-piece on its front 95 lying over but normally out of contact with, two upright pins which at the magnet M are represented by the pins 18-20. Standing over the front end of the lever T and connected metallically by it when the magnet is inactive are similar pins 21-23 which, like the pins 18-20 beneath, are members of circuits that are opened or closed at those points according as the lever T is at rest or out of action, or is attracted and drawn down by the magnet. At the rear or opposite end the lever T is similarly arranged to make contact with one or the other set of contact-pins 30-32, 33-35, according as that end of the lever is depressed or is 110 elevated. When in normal position, or with no current passing through the coils of the magnet M , the lever T at the front end is in contact with the pins 21-23 and completes a circuit between them, but is out of contact with the pins 18-20 beneath the lever. At the rear end the lever T will connect the pins 30-32, but will stand clear of the pins 33-35 above.

The armature-lever of every other magnet in the series M , M^1 , M^2 and so on, operates in the same manner to control the four separate circuits that include as members the upper and lower sets of pins between which the front end of such lever is situated, and the corresponding upper and lower sets of pins at the rear end of the lever. Each of these armature-levers is balanced and adjusted for limited vibratory movements between the pins before described by means 130

of an adjustable stop-screw 190 over the front end of the lever, and a coiled spring arranged to bear upon the lever on the opposite side of the pivot 191.

Instead of being rigidly fixed in their supporting bars all the contact-pins are loosely fitted in sockets for limited vertical play, and are maintained in working position with sufficient play or yielding movement to take the impact of the lever against the end of the pin, by placing a coiled spring 192 on each pin between its carrying bar on the frame and a collar 193 on the pin. This particular construction and arrangement of the contact pins and the armature lever is shown in the detail Fig. 4. A close contact and intermediate metallic connection is by this means always secured between the armature levers and the contact pins, both when the lever is at rest on one set of pins and also when it is brought in contact with the other set of pins when attracted by its magnet. According to this plan of combining with the key-lever of each letter or character in the key-board of the typewriter a particular number of electro-magnets in the series M, M¹ and so on, each letter or character is represented by a group of magnets each of which when energized has the effect to transmit one electrical impulse, and no more, over the line to the opposite station; and these impulses—herein termed selecting impulses—are always in number the same for any given key-lever in the transmitting key-board, so that by one depression of the key-lever the required number of electrical impulses will be transmitted to the opposite station, always corresponding to the number of magnets composing the group that is combined with that particular key in which is always included the last magnet M in the series. The selective impulses thus transmitted by any group of circuit closing levers and their magnets in the series M, M¹, M² and so on, actuate corresponding circuit selecting means in the receiving mechanism at the opposite end; and, as arranged in that part of the apparatus, the circuit depended for its completion on the number of impulses received from the sending end includes the type-bar actuating means of the corresponding letter or character in the typewriter at that station. Upon receiving the number of impulses transmitted from the sending station, therefore, the corresponding number of magnets brought into play operate to complete the required letter- or character-forming circuit to or with the line between the two stations, at the moment that the magnet M¹ situated next to the last magnet M acts on its armature lever, so that the following impulse from the battery E^x which is transmitted by the operation of the magnet M, and is of sufficient greater intensity than the selecting impulses

preceding it, operates to actuate corresponding circuit closing means at the receiving station through which an actuating current will be thrown on the type-bar operating mechanism from a local battery.

In the down-stroke of the key-lever a two circuit-closing contacts 2—3 are brought together and a circuit is completed through the coil of the first one of a group of electro-magnets, composed of the last magnet M in the series, and as many of the preceding magnets in the same series as the fixed number of electrical impulses to be sent over the main-line may require. As, for illustration, in the case of the letter "D", where two relatively weak impulses, followed by a single stronger impulse may be required to operate the corresponding type-bar b^x in the mechanism at the receiving-station, the group of electro-magnets at the sending-station individual to the key "D", such as represented in Fig. 12, will be composed of the last magnet M, and the preceding magnets M², M¹ in the series. By the movement of the armature-levers T², T¹ and T of these magnets, following one another in rapid succession, circuits are successively closed and opened by the momentary contact of the rear ends of the armature-levers with sets of contact-pins 25—27, 29—31, 33—35, situated above them; which contact pins are, as has already been described, loosely supported so as to be free to slide in their supports, and are also spring-held, so that the contacts engaged by one armature lever may be made before those engaged by another are broken, and through these pins and other circuit-controlling pins closed by the same armature-levers circuits are completed and an electrical impulse is sent out on the line W from the battery F, as often as the rear end of each lever in turn rises and touches the contact-pins above it. The magnet M, being the last in the group belonging to the letter "D" receives current from the local battery E^x at the instant that the armature-lever T is attracted to the contact-pins 18—20 beneath its front end. The three armature-levers T², T¹, T are set in operation in this manner by direct current impulses from the battery E at the instant of closing the contacts 2—3 at the key-lever, and three successive impulses are thereupon transmitted over the main-line W, followed by a single impulse of greater potentiality from the battery E^x, by the successive movements of the armature-levers. By increasing the number of magnets and armature-levers in the group, three, four, or more relatively weak impulses and a final impulse of a stronger quality will be transmitted. Each key in the keyboard is connected in this manner into the coil of the first magnet of its individual group, whatever the number of magnets may be, and

the magnet M by which the final impulse of stronger quality is transmitted is always the last magnet of the group.

Referring to Figs. 3, 4, 5 and 6, and particularly to the diagram Fig. 12, it will be seen that each one of the magnets in the transmitting apparatus controls through its armature-lever four separate circuits, or connections, by the movement of the armature-lever between separate sets of contact-pins, arranged in two groups respectively over and under the front end, and over and under the rear end of the lever. The pins in both groups are so placed that with no current in the coil of the magnet its armature-lever will be elevated at the front-end and will rest against the contact-pins of the upper set, but will be out of contact with those beneath; but at the rear end the lever will rest against the lower set of contact-pins, and will be normally out of contact with those composing the upper set. In diagram Fig. 12 illustrating the relative position and arrangement of the last three electro-magnets and their armatures and contact-pins in the series composing the transmitting apparatus for a given letter, as D, it will be seen that one end of the coil of the magnet M² is connected with the contact 3 under the key-lever *a* through the conductors 5 and 8^a; and that, in like manner, the corresponding ends of the coils of the remaining magnets are connected to binding-posts *m*, from which conductors 6 and 7 are carried to the keyboard to connect with the circuit-closing contacts at other keys in the keyboard. Each magnet in its turn is thus separately connected to a set of contacts beneath a key, in order that it may constitute the first one in a given group and be energized directly by the stroke of its key in the keyboard. The coil M² is connected through conductors 8^a and 37 into the contact-pin 17 in the upper set 17-19 standing over the armature T¹ of the second magnet M¹ in the group, and the remaining pin 19 of that set is connected by a conductor 38 directly to one of a series of binding-posts *p*, from which a conductor 39, common to them all, runs to one pole of the battery E. By similar arrangement and connection of all the contact-pins composing the front-sets 10-12, 14-16, and those 17-19-21-23 above the armature-levers T², T¹ and T, as shown in the diagram Fig. 12, the coils of all the magnets in the group M, M¹, M² are in connection with one pole of the battery E before current passes through the first coil M²; but as the remaining side of the coil M², the first in the group of the three magnets M², M¹, M, is in connection with the opposite pole of the battery E through the conductors 8^a, 4-5 in which are interposed the contacts 2-3, the coil M² will receive current only at the moment that the circuit is closed at

2-3, the contacts under the key *a* to which the group of magnets belongs.

A description of the operation of the group of three magnets M², M¹, M and armature-levers T², T¹, T associated with the key *a* (illustrated in Figs. 2, 10 and 12) will make the arrangement of the parts and their functions more clearly understood; and the description will apply, also, to a group or number of armature-levers and the circuit-closing contacts associated with them containing either a greater or a smaller number of magnets and armature-levers. On being depressed, the key-lever *a* closes a circuit from the battery E at the contacts 2-3 over the conductors 5 and 8^a through the coil M² and over the conductors 8^a, 37, to the contact-pin 17 in the upper set 17-19 of armature T¹ of the second magnet M¹, and thence by the contact-pin 19 and conductors 38-39 to the pole of the battery E, and finally through the battery and over the conductor 4 to the contact 2; the front-end of the second armature T¹ at that moment being in contact with the pins 17-19. The coil of magnet M² receiving current from battery E attracts the armature T², and drawing down the front-end of that part against the pins 10-12 immediately sets up a circuit through the coil of the second magnet M¹, which will be traced as follows:—From one pole of the battery E over conductors 58-60-8^b to contact-pin 10, thence by the remaining pin 12 of that set and the connections 8^c and 8^d to one end of the coil of magnet M¹, and through that coil and over the conductors 8^e and 40 to the pin 21 of the two contacts 21-23 composing the upper set over the front-end of armature T; and finally by the conductors 41 and 39 to opposite pole of battery E. Magnet M¹ being energized, draws its armature T¹ away from its upper contact-pins 17-19, thus opening the circuit through magnet M² and releasing the armature T², which thereupon rises at the front end and drops at the rear end. At the same time, armature T¹ being attracted by its coil M¹ connects together the lower set of pins 14-16, with the result to bring in circuit with battery E the coil of the last magnet M. That coil receiving current, attracts its armature T and opens the local circuit through the coil of the preceding magnet M¹ at the instant that the armature T leaves the upper set of pins 21-23 at the front end, and also connects together in circuit the pins 18-20 under the front end of the armature. But while each armature, as it is drawn down by its magnet, acts to open the circuit through the magnet of the preceding armature in the group, it also operates to alternately close and open the main-line circuit by the movement of its rear end between the two sets of contact-

pins through which connection is alternately set up and broken between the battery F and the main-line. The armature-levers being attracted and released at the 5 front end in successive order as their magnets are energized and deenergized one after another in the above manner, transmit the proper number of electrical impulses over the line W to operate the type-bar at the 10 opposite end of the main-circuit. The transmission of these line-impulses in the successive rise and drop of the armatures T², T¹, T in every operation of the group will be seen to take place from the movements 15 of the armatures as follows:—At the instant that the first armature T² is thrown against its contact-pins 25—27, it completes a circuit from one side of the battery F, over conductors 42, 43^a to contact-pin 28 20 under the rear end of the next armature T¹; and as the rear end of that armature-lever is resting at the time on the lower contact-pins 26—28 the circuit is carried through those contacts last-mentioned, and from pin 25 26 through the connection 51 to the contact-pin 27 of the upper set 25—27 standing over the armature-lever T², and hence by the connections 45 and 46 out to the line W. But armature-lever T² being released at the 30 moment that its magnet M² is cut out by the drop of the second armature T¹, will return to position on its lower pins 22 and 24, and opening the circuit at 25—27 will operate to transmit only a single impulse to 35 the line W by the rise and fall of its rear end. For, immediately on being raised from the contact-pins 26—28, the next armature-lever T¹ will open the circuit previously completed through the pins 26—28 40 and conductors 42, 43^a and 51 to the contact-pins 25—27 and so out to the line W over the conductors 45—46. But making contact at the same moment with the upper set of pins 29—31, armature-lever T¹ also 45 connects the battery F to the line W, and an impulse will be transmitted in turn from that battery by the movement of armature-lever T¹. Such circuit will be traced as follows:—From one side of battery F over 50 the conductors 42, 43^b through contact-pins 32—30 with which the first armature T is in contact—that armature still being at rest on the pins,—and thence by the connection 52 and pins 31—29 and connection 47 to 55 conductor 46, and so out to the line W. In this operation it will be seen that each armature-lever in its turn closes the battery F upon the main-line going out from the station; and that while one armature forms a 60 part of the circuit when in a state of rest, the required impulse is transmitted by the movement of the armature-lever behind or to the right; the result of which arrangement is that each armature when attracted 65 by its magnet, also cuts out the previously

energized magnet in the group. Thus, for example, armature T¹ when at rest forms a member of the circuit that includes the coil of the magnet M, because it connects together the contact-pins 17—19. Then, as 70 armature T¹ is attracted by its magnet M¹, it leaves the contact-pins 17—19, and the circuit through the coil of the magnet M² is opened at 17—19. In that movement of the armature T¹, also, a battery-circuit is closed 75 through the coil of the next magnet M at the moment the armature touches the contact-pins 14—16, and armature T is drawn down against the contacts 18—20, cutting out the coil of the magnet M¹ by opening 80 its circuit at 21—23. The coils of the last magnet M are connected in circuit with one side of the battery E at the moment that the armature lever T¹ is attracted to its magnet, at which moment the contact-pins 85 14—16 being connected by the lever complete the circuit through the contact-pin 16 to one end of the coil M; and the opposite end of the coil being connected to the last binding post m at that end of the frame by 90 the conductor 8^c, the conductor 39 running from the binding post to the remaining side of the battery E completes the circuit through the last coil M. The final operation of sending current to the line from 95 battery E^x is completed when the armature-lever T, being attracted to the poles of the magnet beneath it, connects together the lower set of contact pins 18—20 at the front end and the upper set 33—25 at the rear. 100 The current from battery E^x augmenting that from battery F, supplies the necessary strength of current for the final impulse that follows the series of circuit-selecting 105 impulses from the battery F; and by this stronger impulse the selected type-bar at the receiving-station is operated. 110

In the above described manner every magnet-coil is separately connected with one side of the battery E through circuits that are 115 normally open at contacts as 2—3, under a letter-key; so that while each magnet may constitute in turn the first or leading one in a series of magnets which are associated with a particular key, every magnet with its 120 armature and contact-pins also composes one member or unit in several other series, according to its position in the whole number or series. As, for example, magnet M² becomes the leading-coil in the series composed of magnets M², M¹, M, when the particular key with which it is associated is depressed to type-write the letter at the receiving-end 125 corresponding to the particular key struck in the transmitting key-board; but it also forms an intermediate coil in other series, as for example, when the magnet M² is made the second unit in another group by the addition of the next magnet to the right, which would be magnet M³, if it were shown 130

in the diagram Fig. 12. Magnet M^2 then would receive current from battery E through the circuit controlled by magnet M^3 and its associated armature, in the same 5 manner as the other intermediate coils.

The means situated at the receiving-end of the line through which the impulses from the sending-station operate to select the circuit of a particular letter-forming means 10 and to actuate the same, consist of a series of circuit-controlling armatures, contacts and magnets, similar in arrangement and operation to those in the transmitting apparatus, with the exception, chiefly, that each armature lever in the series U , U^1 , U^2 and so on 15 when attracted to its magnet remains down, instead of being immediately released after its attraction. In that position it is retained by its magnet, with the effect both to connect the local operating circuit of a given letter-actuating mechanism with the main-line, and also to connect the coil of the next magnet in the series in circuit with the main-line in such manner that each incoming 20 impulse of relatively low potentiality after the first impulse, will bring in action and set an additional circuit-completing armature, until the number of armatures attracted and held down shall equal the number 25 of such selecting-impulses; after which, the final impulse of relatively high potentiality completes the operation of throwing current from the local battery G on the solenoid-coil of the selected type-bar through 30 the circuit completed by the last armature in the group.

The electro-magnet or solenoid of each type-bar is individually connected by one end of its coil into one pole of battery G by 35 a line of conductors 112—114—116, normally broken at contact-pins 108—110, which are connected together by the contact of a circuit-closing armature I with the ends of those pins, as often as that armature is attracted to the poles of the electro-magnet H in the main-line. The remaining end of each solenoid-coil is connectable into the opposite pole of battery G through separate circuit-forming conductors and connections, in 45 which one particular armature-lever of the series U constitutes the controlling-member, and which by its movement as attracted and held down by its own coil in the series N , completes the remaining side of the particular 50 operating circuit that brings in the solenoid and battery G . The means through which the incoming impulses are caused to select and connect in circuit with battery G the operating solenoid of a particular type-bar in the writing-mechanism, according to the number of transmitted impulses, will be described with reference to the diagram, Fig. 55 13, in which are illustrated six sets of electro-magnets N to N^6 , inclusive; the armature levers U to U^6 , inclusive, associated with

them, together with the operating-circuit of one solenoid and its type-bar. With each of the electro-magnets in the series N is associated an armature lever of a series U , which levers are preferably pivotally supported 70 upon a common shaft 191^a. These levers carry at their front ends, that is, the ends nearest their electro-magnets, contact pieces adapted, when the armatures carried by the levers are attracted, to make engagement 75 with spring-held contact pins arranged in pairs so that each lever when attracted electrically connects two of them, these contacts being designated in Figs. 13, 84, 86, 88, 90, 92, 94, 96, 98, 100, 102, 104 and 106. The front 80 ends of these levers of the series U carry contact plates each adapted to engage with a pair of contacts below and with four contacts above, the lower contacts for the lever U being designated 60 and 62, and the upper 85 contacts designated 59, 61, 63 and 65, see Figs. 7, 8 and 13. These pins are spring held and yielding so as to have a limited amount of movement in their guides, as is represented in Fig. 9. The first pin of each 90 series, that designated 59 for the lever U , and that 69 for the lever U^1 , carries a contact spring which is adapted to extend over and be engaged by one of the movable pins of the series to the right when such pins are 95 elevated by the attraction of the armature lever by its electro-magnet. Thus the pin 65 of the first series, that of the lever U , when lifted engages with the spring 67, which constitutes a bridge between the pins 65 and 100 69, for a purpose which will be presently described. The particular type-bar b^x indicated in that diagram being considered for purpose of illustration as the one that is actuated by three impulses from transmitting means similar to those illustrated in Fig. 12, it should be understood that the solenoid s and its core t connected to the key-lever a^x cause the type-bar b^x to imprint the letter D , as often as current is passed 105 through coil s from the local battery G . The second solenoid s^1 indicated in the diagram is part of the actuating-means of another type-bar in the writing mechanism, not shown in the diagram. 110

Solenoid s is connected to one side of the battery G by conductors 116—114—112. Leading from the opposite end of its coil the conductor 118 terminates at the contact-pin 89 standing above the armature-lever U^3 , 115 120 and from that point connection with the remaining side of the battery G is completed through the contact-spring 87 on the head of the pin 89 and the pin 85. The break in the circuit at these contacts 89 and 85 will 125 be closed, and the solenoid receive current as often as the contact-pin 85 being lifted by armature-lever U^2 touches the contact-spring 87 carried by pin 89. Lever U^2 thus controls the particular solenoid s that has for one of 130

its circuit-closing contacts the pin 85 over the rear end of lever U^2 , and for its other contact the pin 89 over the rear end of the adjoining lever U^3 . The result of this arrangement is that it requires two weaker impulses to bring into play and energize the magnets N , N^1 , and a stronger impulse to energize the magnet N^2 to draw down in succession their armatures U , U^1 and U^2 .

10 The circuit thus completed at the moment that lever U^2 touches the contact-pins 85—89, is the one that includes the coil of the solenoid s . But until the preceding levers U and U^1 are attracted and held down by their 15 magnets N , N^1 , the third lever U^2 will not come in play. Two weaker impulses are thus necessary to select and set the lever U^2 for operating the solenoid s .

All the impulses transmitted by the sending apparatus pass through the windings of the magnet H before reaching the circuit selecting magnets of the receiving apparatus, but that magnet being wound for the required resistance, and its armature-lever I 25 being adjusted by regulating the tension of the coiled spring I^2 in the well known manner, it will not be energized by the impulses of lower potentiality, and the armature-lever I will not be attracted as long as the 30 weaker impulses are received from the battery F at the sending station. These impulses therefore pass through the coils of the magnet H without affecting it; but on receiving the final impulse which is of a 35 sufficient potentiality to act on its coils, the magnet H attracts the armature I with the effect to close a local circuit that is normally open at the contact-pins 108—110 under the pole-piece of the armature I . The battery 40 G included in this local circuit is arranged to supply current of the required potentiality to actuate the type-bar operating means which are connected in such local circuit through the circuit selecting devices 45 which are actuated by the weaker impulses preceding the last and stronger impulse, as I will now proceed to explain:—The first incoming impulse passing through the coils of the magnet H and over the conductor 177 50 and connections 134 to the contact pin 60 in the set under the armature lever U reaches the coils of the first magnet in the series N , N^1 , N^2 and so on, through the contact-pin 62 of the pins 60—62 on which the armature-lever 55 is normally resting. That contact-pin being connected with the coils of the magnet N through the conductor 140, the circuit through the magnet is carried to the return conductor 182 over the connecting wire 183, 60 and thence to earth at g ; thereby completing the circuit through the earth back to the sending station. When a full metallic circuit between the stations is employed a return wire 184 is substituted for the earth-return. The first of the series of weaker im-

pulses thus acting on its magnet sets the lever U . On receiving current, coil N draws the front end of lever U down against the two contact-pins 84, 86, and also raises the rear end off the contacts 60—62, and at the 70 same moment presses it against the contact-pins 59, 61, 63, 65, the effect of which is to raise and hold up those four pins in their guides.

It should be understood that all the contact-pins have a limited movement in their guides, and are returned to position by a light coiled-spring on each pin at the moment that the pressure of the lever is removed, the extent of their movement being governed 80 by collars on the pins, the arrangement being similar to that of the contact pins illustrated in Fig. 4. By contact of lever U with the pins 84—86, coil N is brought in circuit with the holding-down battery F^2 , 85 and current is thrown on coil N , the effect of which is to hold the lever U in its depressed position with its rear end against the upper contact-pins 59—61, 63—65. Current then will flow from one pole of battery F^2 90 over conductor 160 and the connection 180 at the first binding-post on the right to the pin 84, and thence to the next pin 86 of that pair under the depressed front end of the lever U , and by the connection 184 to one side of the coil N . The return to the opposite pole of battery F^2 is completed over the connection 140 to binding-post y , and thence over conductors 168, 160 and 161 to a set of contacts $e-f$ located under the lever d^x of the spacing-mechanism on the typewriter. These contacts $e-f$ are so arranged in the holding-down circuit that the circuit remains closed at that point, and current is maintained on the magnet-coils until after the type-bar has operated; but as soon as its letter or character is written and the spacing-mechanism comes into action to move the paper for the next letter, the lever d^x is moved in the return of the key-lever to 100 position, and contacts $e-f$ are caused to separate and thereby momentarily open the holding-down circuit at that point, but are brought together again as the spacing-mechanism comes to rest. The last-mentioned circuit therefor remains closed at the point $e-f$, except in each movement of the spacing-mechanism, when it is opened for a sufficient interval to throw off the coils of all the levers previously selected and set by 110 the stroke of the key that was last struck in the transmitting key-board.

In addition to the two circuits set up by the lever U , the coil N is cut off from the main-line as the lever U leaves the contacts 60—62, and connection is set up between the line and the next coil N^1 at the moment that the lever touches the pins 61—63. The second coil being then connected with the line 125 177 through pins 61, 63 and the connection 130

131 and the pins 64—66 already connected together by the lever U^1 , the second impulse passes over the circuit thereby set up, and over the wire 142 from the pin 66 to one 5 end of the coil, and is completed from the other end of the coil to the return side of the main-circuit over the connection 121 and the conductor 182 to "earth" at g . As the lever U responds to the first incoming impulse 10 it cuts off its own actuating coil from the line and connects it in circuit with the holding-down battery F^2 at the same instant that it sets up connection between one side of the next coil N^1 and the main-line; 15 whereupon the second incoming impulse reaching the second coil N^1 over the circuit 177, 61, 63, 131, 64, 66, 142, and thence to the return-conductor 182 and to the earth at g , puts current on the coil N^1 with the effect to 20 draw down the armature-lever U^1 . That movement of the second armature-lever thereupon cuts out its coil N^1 and throws it in circuit with the holding-down battery F^2 ; at the same time connecting the coil N^2 into 25 the main-line connection 177. The third incoming impulse which is stronger than the two which preceded it then acts through the coil N^2 to operate the third armature-lever U^2 in the series. The actuating circuit 30 of the third coil N^2 will be traced from the line 177 through the second and third pins 71—73 standing above the second lever U^1 , to the conductor 133, thence to the pins 68—70 under the third lever U^2 and the conductor 144 to the coil N^2 . All the coils being connected permanently into the main-circuit return through the common conductor 182 and the wire 183 running from one side of each coil to the return-conductor, 35 40 it will be seen that a coil receives current from the main line whenever a circuit is completed from the line to the remaining side of the coil through the lower contact-pin of its own armature-lever and the upper contact-pins of the next lever to the right. It will be seen, also, that each armature-lever at the instant it is attracted by its own coil throws the coil in circuit with the holding-down battery F^2 . And lastly, it will be 45 50 seen that every armature-lever at the time of its attraction is not only held down as long as the holding-down circuit remains closed at the points $e-f$ in the type-writing mechanism, but it also sets up a condition 55 between the solenoid-coil s and its local actuating battery, whereby the coil will receive current and the type-bar will be operated at the instant that the solenoid-circuit is closed at the contacts 108—110. Under 60 65 the conditions above described, therefore, the number of weaker impulses as transmitted by a given key determine the number of armature-levers that must be operated in order to select and set up the required solenoid circuit for actuating the

proper type-bar; and the last stronger impulse of the series operating directly on the coil of the magnet H closes the local circuit of the selected solenoid.

To every solenoid in the type-writing mechanism there is associated a particular armature-lever, which at the time of its attraction puts its solenoid in condition to receive current from the local battery G . But every armature-lever, at the time of its attraction also connects the actuating-means of the next armature-lever to the left into the main-line ready to be acted on by the following impulse. The result of this is that if the impulse be a stronger impulse, it 70 will act directly on the coil of the magnet H , and by closing the local battery-circuit at 108—110, will actuate the selected solenoid; or, if the following impulse be also a weaker, and not a stronger impulse than the preceding one, the coil H will not be energized, the contacts 108—110 will not be closed at that moment, and the coil of the next armature-lever being acted on by such weaker impulse 75 will be energized, thereby bringing a different solenoid in circuit to be operated by the next impulse if that impulse should be of the required strength to energize the magnet H in the main-line. 80 85 90

The principle on which the selection and the operation of a particular type-bar actuating solenoid is effected over a single-line main circuit by a single depression or stroke of a transmitting key at one end, and the receiving apparatus at the other end, is 95 100 105 110 115 120 125 130 that a particular number of weaker impulses in rapid succession act to select the armature-lever associated with the particular solenoid to be actuated, after which the final stronger impulse acts to close the local battery on the selected solenoid and thereby complete the operation. Any particular key selected and struck at the transmitting-key-board will thus operate the corresponding type-bar at the receiving-end by currents of one direction, and the desired end and object are attained without the employment of polarized relays, or the use of synchronized apparatus. At the end of the operation and as the type-bar returns to its position of rest after having made contact with the paper, the holding-down circuit is automatically opened at the points $e-f$, and all the coils in the series N that had previously been brought in play, are immediately deprived of current. The armature-levers that were acted on by the selected coils there-upon return to position ready to respond to the next series of in-coming impulses. In the receiving apparatus as thus constructed to attain the desired object of selecting and operating a type-writing mechanism by means of electrical impulses transmitted over a single main-line or circuit by a single stroke of a transmitting key, as many circuit-selecting

levers and their associated contacts are provided as there are type-bars or parts in the type-writing mechanism to be actuated. It will be seen further, that the position in the 5 series of circuit-selecting levers of the particular lever to be actuated in order to operate a given type-bar or part, governs and determines the number of impulses to be transmitted to the receiving apparatus from 10 the transmitting key-board at the opposite end of the circuit.

Having thus described my invention, what I claim is:—

1. The herein described system of operating type-writing mechanism on a single main-line circuit, consisting in a transmitting key-board at one station containing a separate key for each letter or character provided in the type-writing mechanism at 20 another station on the line; means operating through the single stroke of a key to send out on the line a fixed number of relatively weak electrical impulses, the number of which is always individual to that key, 25 followed by a final electrical impulse of greater strength than the initial impulses; in combination with type-bar actuating means in the writing-mechanism at the receiving-end of the line including electrically 30 actuated means for operating each type-bar, in normally open circuit with a local battery, circuit-selecting means actuated by the relatively weak initial impulses for putting in operative condition with the local battery 35 the electrically-actuated means of a particular type-bar according to the number of such initial impulses transmitted on the line by the stroke of the selected key, and means actuated by the final stronger impulse operating to close the local battery in the selected 40 type-bar actuating means.

2. The combination, with a type-writer key-board, of a local battery, a main-line, a plurality of circuit making and breaking devices each adapted when operated to send a 45 single impulse from said local battery out on the main-line, an electro-magnet to each

circuit making and breaking device adapted when energized to actuate the same; means connecting said magnets in series and in 50 groups separately with every key in the key-board, each group consisting of a fixed number of magnets, but the last magnet in the series being common to all the groups, a local circuit including a battery for energizing the magnets, means controlled by each separate key for putting the magnets composing its particular controlling group in circuit in successive order with the said battery, whereby the magnets of each group 60 operate under a single stroke of the controlling key in the key-board to actuate the main-line circuit making and breaking devices in successive order, and means actuated by the last magnet in the series as the 65 same is energized and adapted to send out on the main-line a final impulse of greater strength than the initial impulses.

3. In an electrically operated system for conveying intelligence between stations on 70 a single main-line circuit, the combination of a key-operated circuit making and breaking device adapted to send over the line from a transmitting station a fixed number of relatively weak impulses individual to 75 the key, followed by a final impulse of greater strength than the preceding impulses; a type-bar operating mechanism at the receiving-station in the line, including a solenoid adapted to respond only to the fixed 80 number of weak impulses transmitted over the line by operating the associated key in the key-actuated means at the other station on the line, said circuit-selecting means operating under the series of weak impulses 85 to connect its solenoid in circuit with one side of the solenoid-operating battery, and means operated by the final stronger impulse on the line for completing the selected solenoid-circuit.
